UNITED STATES PATENT OFFICE.

FREDERICK DENNETTE, OF HYDE PARK, MASSACHUSETTS.

RAILWAY SAFETY SYSTEM.

1,308,002.

Specification of Letters Patent. Patented June 24, 1919.

Application filed March 6, 1918. Serial No. 220,823.

To all whom it may concern:

Be it known that I, FREDERICK DENNETTE, a citizen of the United States of America, and resident of Hyde Park, in the county of 5 Suffolk and State of Massachusetts, have invented new and useful Improvements in Railway Safety Systems, of which the following is a specification.

This invention relates to a safety system 10 for railways and the like and more particularly to a block system for preventing collisions. Mechanism carried by a train is arranged to be controlled by conditions along the trackway affecting the safety of the 15 train. The train mechanism may be employed to operate the throttle, the brakes, signals or other devices, and it is preferably arranged both to close the throttle and to set the brakes when the trackway is 20 obstructed.

The principal objects of the invention are to provide a safety system which is simple in construction and reliable in operation, which will prevent trains running too close 25 together, which will stop a train when it approaches another train too closely, which will permit the trainmen to reverse the train after being stopped but which will prevent the trainmen from proceeding after being 30 stopped until valve mechanism beneath the train has been reset, and which affords other novel advantages hereinafter appearing.

In the accompanying drawings,

Figure 1 is a plan view of a trackway 35 and associated apparatus;

Fig. 2 is a side elevation of train mechanism for controlling the throttle, parts being shown in section;

Fig. 3 is a top plan view of the mechanism 40 shown in Fig. 2;

Fig. 4 is a side elevation of a train valve adapted to be operated by members distributed along the trackway;

Fig. 5 is an end elevation of the train 45 valve viewed from the right of Fig. 4;

Fig. 6 is a vertical, longitudinal, central section of the train valve taken on line 6—6 of Fig. 5;

Fig. 7 is an end elevation of one side of the 50 track mechanism such as shown in Fig. 1; and

Fig. 8 is a diagram showing the relationship of the various parts of the mechanism carried by the train.

55 In the particular embodiment of my invention illustrated in the drawings the trackway,

comprising rails 1 and 2, is divided into a plurality of blocks B₁, B₂, etc., each block being divided into two sections S₁ and S₂, the portions of the rails of the respective blocks and sections being insulated from one another in any suitable manner. Distributed at intervals along the trackway in association with recurrent sections are actuating members A, A', etc., which are arranged to actuate train-carried mechanism when in operative position and to clear the train-carried mechanism when in inoperative position. One of these actuating members is associated with each block and is preferably disposed at the 60 junction of the two sections of each block. The actuating members are rotatably mounted to be swung either into an upright position shown in dotted lines in Fig. 7 or into a horizontal position shown in full lines in 65 Figs. 1 and 7. A stop 3 is preferably mounted on the trackway immediately in advance of the actuating member to stop the member in upright position.

The shaft 4 carrying the actuating member at its inner ends is provided at its outer end with a gear wheel 5 and the shaft is journaled in an upright member 6 disposed on the outside of the gear wheel 5. Stops 7 and 8 are mounted on the upright 6 to co-operate with a pin 9 on the gear wheel to stop the gear wheel when the actuating member reaches its upright position and its horizontal position respectively. Journaled in upright 6 are two shafts 10 and 11 which are 70 respectively connected to two motors 12 and 13 at their outer ends and to pinions 14 and 15 at their inner ends, the pinions 14 and 15 being arranged to mesh with the gear wheel 5. The motor 12 is connected across section S₂ 75 through a battery 16 by means of conductors 17 and the motor 13 is connected across section S₁ through a battery 18 by means of conductors 19. The motors are so constructed and the batteries are so connected thereto 80 that, when the respective circuits are closed by the presence of trains in the respective sections of the block or by other short circuit of the trackway, the motors will tend to 85 rotate in opposite directions as indicated by 90 the arrows in Fig. 1.

The train-carried mechanism comprises a valve 20 associated with the air system of the train as hereinafter described. The actuating lever of valve 20 is formed in two 95 parts, 21 and 22, the two parts being pivotally connected together at 23. A spring 24

is mounted on the inner part 21 by means of screws 25 so as to engage the part 22 and hold the two parts in folded relationship as illustrated in Fig. 4. The valve 20 is mounted on the lower portion of the train so that the portion 22 of the handle will engage the actuating member A on the trackway when the actuating member is in upright position. If the actuating member engages the lever 22 on the left-hand side (Fig. 4) the valve will be rotated. However, if the actuating member engages the lever on the right-hand side (Fig. 4) the part 22 will swing about the pivot 23, the friction of the valve preventing the rotation of the handle 21, so that the valve 20 will not be actuated.

The train-carried mechanism also comprises a cylinder 26 and a piston 27 coöperating with the throttle lever T or other suitable control lever on the train. The throttle lever T, as illustrated in Figs. 2 and 3, is of the ordinary construction and comprises a lever 28 pivotally mounted at 29, a segmental rack 30, a catch 31 pivotally mounted on the lever 28 to engage the rack 30 and hold the throttle in adjusted position, and a release handle 32 for withdrawing catch 31 from the rack 30 when it is desired to actuate the throttle. On the forward end of the piston rod 33 is provided a U-shaped yoke 34 whose arms 35 and 36 extend along opposite sides of the throttle bar 37. The yoke 34 is connected to the throttle bar 37 by means of a bolt 38 extending through slots 39, the arms 35 and 36, through the throttle bar and through the throttle lever 28 (Figs. 2 and 3). The openings 39 in the yoke arms 35 and 36 are elongated horizontally to form slots adapted to permit the bolt 38 to slide therealong. Extending downwardly from the catch 31 through the opening 40 in the yoke 34 is a lever 41 adapted to withdraw the catch 31 from the rack 30 when moved forwardly.

Thus when the piston 27 in cylinder 26 moves forwardly the base of the yoke 34 first engages the lever 41 to withdraw the catch 31, the throttle lever being unaffected during the initial movement of the piston 27, and after continued movement of the piston the rear ends of the slots 39 engage the bolt 38 and swing the throttle forwardly thereby shutting off the propulsive power. A relief valve 45 is provided in the cylinder 26 to permit air to escape therethrough when the air pressure attains a predetermined value and thereby prevent the pressure exceeding the predetermined value.

The preferred arrangement of the various parts of my improved system which are carried by the train is illustrated in Fig. 8 where T is the throttle illustrated in Figs. 2 and 3, B is the valve for controlling the brakes of the train, and R is the lever for reversing the train. The valve 20 shown

in detail in Figs. 4, 5 and 6 is disposed in a pipe line 42 leading from the air brake pipe 43 to the cylinder 26. The reverse lever R is connected to a valve 44 disposed in the pipe 42 at a point between the valve 20 and the pipe 43. As shown in Fig. 8 the brake valve B is normally open to admit air to the brake system, the valve 44 is also normally open, but the valve 20 is normally closed so as to cut off the air pressure from the cylinder 26. The valves B and 44 will ordinarily be located in the engine cab along with throttle T, reverse lever R, and cylinder 26, but the valve 20 will be located at a point beneath the train adjacent the trackway so as to engage the actuating members A along the trackway when the latter are in upright position. In order to maintain the valve 20 at a substantially constant distance from the track the valve is preferably mounted on the axle of the train or on some other part beneath the springs.

The operation of that portion of the system associated with the trackway is as follows: The actuating members A normally stand in upright position when a train passes along the trackway in the direction of the arrow in Fig. 1, which is the normal direction of travel. The circuits for the motors 12 and 13 are successively closed by the wheels and axles bridging the two rails. When the train enters the first section S₁ of a block the circuit 19 for motor 13 is closed, thereby rotating the actuating member into horizontal position. This is the inoperative position of the actuating member and when in this position the train passes over the member without the member engaging the valve lever 22. When the train has passed entirely into the second section S₂ of a block the circuit 17 for motor 12 is closed, thereby throwing the actuating member into upright position. Owing to the fact that the motors 12 and 13 are connected to the actuating member in opposition, the actuating member is unaffected when both motors are energized simultaneously. The actuating member A is therefore not thrown from horizontal into upright position until the train has entirely left the first section S₁. Inasmuch as the entire train must pass the junction between the two sections before the actuating member A is thrown into upright position, the control lever 22, if placed on any car of the train will pass over the actuating member before the member is thrown into upright position. However the lever 22 will usually be carried by the engine.

Thus in the normal operation of the system each of the actuating members normally stands upright in operative position, is thrown down into inoperative position when a train enters a block and is thrown up into operative position after the train has passed entirely into the second section of the block.

However, should the second section S_2 of the block be obstructed by a train or other obstruction the actuating member A is not thrown down into inoperative position upon a train entering the first section for the following reason. The circuit of motor 12 would be closed by the train in the second section of the block and the closing of the circuit 19 by the train entering the first section would be ineffective to operate the actuating member for the reason that the motor 13 would be opposed by motor 12. Actuating member A would therefore remain in operative position and upon the train reaching the junction between the two sections the actuating member would engage the lever 22 to open the valve 20 and stop the train.

The operation of the portion of the system carried by the train is as follows: When the valve 20 is closed as is normally the case, the throttle T may be operated in the usual manner, the piston 27 not being carried forward or backward with the throttle and being unaffected by the air pressure in the brake system inasmuch as the valve 20 is closed, and the brake valve B may be operated in the usual manner to operate the brakes. However, when the valve 20 is open, by engagement with an actuating member A as above described, air pressure is admitted to the cylinder 26 thereby closing the throttle. After the valve 20 is opened the throttle T can not be operated by hand inasmuch as the pressure behind the piston 27 is so determined as to prevent such operation. The relief valve 45 is so set that the pressure in the brake system will fall to such a value as to apply the brakes but will not fall to such an extent as to permit the throttle T to be operated by hand. Thus the train will be stopped when the valve 20 is opened and the train can not be started ahead until the engineer dismounts and closes the valve 20 which, as above stated, is beneath the train. However, the train can be reversed while the valve 20 is open in the following manner: When the reverse lever R is thrown into reverse position the valve 44 is closed thereby cutting off the cylinder 26 and closing the air brake system so that the brakes are released and so that the throttle can be actuated to back the train. However, the train can only be moved backward and not forward since the pipe 42 will be opened when the reverse lever is thrown into the normal position shown in Fig. 8. In reversing the train the valve 20 will not be closed upon engagement with member A because of the joint 23 in the valve lever above described.

If a train or other obstruction is present in the second section of the block the train entering the second section will be stopped as above described and ordinarily will back

into the first section to wait until the second section is clear. When the second section becomes clear the actuating member A will be thrown into inoperative position by the presence of the train in the first section and this train can then proceed. In practice a signal would be associated with the actuating member A and associated mechanism to indicate whether the actuating member A is in operative or inoperative position. 75

I claim:

1. A railway safety system comprising actuating members distributed along the trackway at intervals so as to actuate train mechanism when in operative position and so as to clear the train mechanism when in inoperative position, means for throwing the respective members into inoperative position when approached by a train, and means for throwing the respective members into operative position after being passed by a train, said second means being connected with said first means so as to render the first means inoperative when the track is obstructed. 90

2. A railway safety system comprising a trackway divided into sections, actuating members associated with recurrent sections so as to actuate train mechanism when in operative position and so as to clear train mechanism when in inoperative position, means associated with the respective sections preceding the said members for throwing the respective members into inoperative position when approached by a train, and means associated with said succeeding sections for throwing the respective members into operative position after being passed by a train, said second means being arranged to render the first means inoperative when a succeeding section is occupied by a train. 95

3. A railway safety system comprising a trackway divided into blocks, each block being divided into sections, an actuating member associated with each block so as to 110 actuate train mechanism when in operative position and so as to clear the train mechanism when in inoperative position, means responsive to the presence of a train in one of said sections for moving said member into operative position, and means responsive to the presence of a train in another of said sections for moving said member into inoperative position, said two means being opposed to each other so that said member is not moved when a train enters 115 one of said sections if a train is present in the other of said sections. 120

4. A railway safety system comprising an actuating member disposed along the trackway so as to actuate train mechanism when in operative position and so as to clear the train mechanism when in inoperative position, motor means for operating said member, an electric circuit connecting said 125 130

- means with one section of the trackway to move said member into operative position when a train is entirely in the section, and an electrical circuit connecting said means with a succeeding section of the trackway to move said member into inoperative position when a train is entirely in the latter section.
5. A railway safety system comprising an actuating member disposed along the trackway so as to actuate train mechanism when in operative position and so as to clear the train mechanism when in inoperative position, motor means for operating said member, an electrical circuit connecting said means with one section of the trackway to move said member into operative position when a train is entirely in the section, and an electrical circuit connecting said means with another section of the trackway to move said member into inoperative position when a train is entirely in the latter section, said circuits being connected to the motor means differentially so as to be inoperative to move said member when trains are in both of said sections at the same time.
6. A railway safety system comprising a trackway divided into blocks, each block being divided into sections, an actuating member associated with each block so as to actuate train mechanism when in operative position and so as to clear the train mechanism when in inoperative position, motor means for operating said member, an electrical circuit connecting said means with one of said sections to move said members into operative position when a train is in the section and when the other section is clear, and an electrical circuit connecting said means with the other of said sections to move said member into inoperative position when a train is in the latter section and when the former section is clear.
7. A railway safety system comprising a trackway divided into blocks, each block being divided into sections, an actuating member associated with each block so as to actuate train mechanism when in operative position and so as to clear the train mechanism when in inoperative position, a motor connected to said member to move the member into operative position, a second motor connected to said member to move the member into inoperative position, and circuits respectively connecting said motors to said sections so as to energize the motors when trains are present in said sections, said motors being connected to said member in opposition so that the member remains unmoved when both motors are energized.
8. A railway safety system comprising a trackway divided into blocks, each block being divided into sections, an oscillatory member associated with each block so as to actuate train mechanism when in operative position and so as to clear the train mechanism when in inoperative position, a gear wheel for oscillating said member, two motors respectively connected to said sections so as to be actuated by the presence of trains in the sections, and gears connecting said motors to said gear wheels in opposition, whereby said member is moved into operative position by a train entirely in one section and into inoperative position by a train entirely in the other section and is unaffected by a train entering one section when a train is present in the other section.
9. A railway safety system comprising a train control lever, a segmental rack, a catch pivotally mounted on said lever for engagement with said rack and provided with a downwardly extending arm, a cylinder, a piston in said cylinder, a rod connecting the piston with the control lever having a bifurcated yoke upon its forward end embracing said arm, a pin and slot connection between said control lever and said yoke whereby upon initial movement of said piston, said catch is withdrawn from said rack and upon further movement of said piston, said lever is operated.
10. A railway safety system comprising a train control lever, a reverse lever, track actuated means for throwing said control lever to the stop position and locking it against movement, and means under control of said reverse lever for unlocking said control lever whereupon said control lever may be moved to the running position only for the purpose of reversing the movement of the train.
11. A railway safety system comprising a train control lever, a reverse lever, track actuated pneumatic means for throwing said control lever to the stop position and locking it against movement, and means under control of said reverse lever for unlocking said control lever whereupon said control lever may be moved to the running position only for the purpose of reversing the movement of the train.
12. A railway safety system comprising a train control lever, a reverse lever, a cylinder, a piston in the cylinder, a rod connecting the piston with the control lever, a connection from the airbrake system to said cylinder, track operated means for opening said connection whereby said control lever is actuated and maintained actuated by pressure in said cylinder, and a second means under control of said reverse lever for again closing said connection whereby the pressure is released to permit movement of said control lever to reverse the movement of the train.
13. A railway safety system comprising actuating means distributed along the trackway at intervals so as to actuate train mechanism when in operative condition and so as

not to actuate train mechanism when in inoperative condition, means for placing the respective actuating means in inoperative condition when approached by a train, and 5 means for placing the actuating means in operative condition after being passed by a train, said third means being associated with

said second means so as to render the second means inoperative when the trackway is obstructed by a train. 10

Signed by me at Boston, Massachusetts, this nineteenth day of February, 1918.
